REGENERATING AIR HEATER SYSTEM

Georg Bender, Leuna, Kreis Merseburg, and Alfred Krauthakel, Bad Durenberg, Kreis Merseburg, Germany, assignors to VEB Leuna-Werke "Walter Ulbricht," Leuna, Kreis Merseburg, Germany

Application November 15, 1955, Serial No. 546,926

3 Claims. (Cl. 263—19)

This invention relates to arrangements for use in connection with blast furnaces, low shaft blast furnaces, and apparatus for the manufacture of city gas or synthetic gas, especially to the systems of regenerating air heaters and regenerating gas heaters of the type also known as "Cowper's stoves" for use in connection with blast furnaces.

Hitherto customary multi-regenerating air heater systems comprising a plurality of regenerating air heaters of the type also known as "Cowper's stoves" are fitted and lined with refractory stonework. When such customary multi-regenerating air heater systems are used for the operation of blast furnaces, the flue gases and the blow air or blow gas enter the places of action in the blast furnace with heavy periodic fluctuations of the temperature, which may amount up to 350° C. in systems having two Cowper's stoves. At the start of a period of blowing the blow air or blow gas is heated to a maximum temperature by the very hot stones of the lining. Then, during the period of blowing a portion of the accumulated heat is transferred to the blow air or blow gas whereby the temperature of the stones of the lining is reduced to a great extent so that the blow air or blow gas leaves the Cowper's stove at a lower temperature at the end of the period of blowing. During the period of heating similar phenomena occur, i.e. at the start of the period of heating the flue gases leave the Cowper's stove at a comparatively low temperature and at the end of the period of heating at a higher temperature. These fluctuations of the temperature disturb very much conditions for a uniform operation at the place of action in the blast furnace.

In order to overcome said disadvantages it has been proposed to add a third Cowper's stove to such a system. Although the fluctuations of the temperature are less in such systems comprising three Cowper's stoves, they still range up to 200° C. depending on the method of operation.

For the operation of blast furnaces it also has been proposed to control automatically these disadvantageous fluctuations of the temperature of the hot blow air or blow gas leaving the Cowper's stove by adding cold air by the so-called cold blast valve so that a blast temperature as uniform as possible is maintained from the beginning to the end of the period of blowing. This is done customarily in such a way that the cold blast valve is turned off periodically, so that it is closed at the end of the period of blowing with the result that the blow air or blow gas reaches the blast furnace at the exit temperature of the Cowper's stove, while at the start of the period of blowing so much cold air is added that, prior to the entry of the air or gas into the blast furnace, the exit temperature of the Cowper's stove, being at this time much higher, is reduced to a temperature substantially equal to the exit temperature of the Cowper's stove at the end of the period of blowing.

An object of the invention is to overcome the disad-

vantages of the hitherto customary multi-Cowper's stove systems.

According to the present invention, means are provided to produce a substantially constant temperature 5 of the hot gases which enter the place of action of the reactor from the Cowpers. Such means comprise a heat accumulator through which the hot gases pass on their way to the reactor. The heat accumulator acts as a heat equalizer, collecting and storing heat from the hot gases 10 at the beginning of the operating period of the Cowper, and later transferring the stored heat to the cooler gases which leave the Cowper at the end of the operating period. Thus, the gases are fed to the reactor at a substantially constant temperature over the entire period of operation of the Cowper. This is particularly useful in blast furnace operation, where the gases fed to the blast furnace should be as hot as possible and at the same time as uniform in temperature as possible. In addition, it is useful in production of city gas from low temperature 20 carbonization gas, synthetic gas production, and the like.

Another object of the present invention is to provide a multi-Cowper's stove system of the character described, by means of which undesired fluctuations in the temperature of the gas emitted thereby may be avoided. This 25 is done without unduly decreasing the over-all temperature of the gas, as results from the "cold blast valve" method previously described.

Still another object of the invention is the provision 30 of a multi-Cowper's stove system of the character described which may be incorporated into existing regenerating air heater or gas heater systems.

A further object of the invention is the provision of a 35 multi-Cowper's stove system of the character described in which a heat accumulator is provided for equalizing the temperature of the air or gas emitted by each Cowper during the blowing period, and a second heat accumulator is provided for equalizing the temperature of the burned heating gases emitted from each Cowper during the burning period.

Other objects and structural details of the invention 40 will be apparent from the following description when read in conjunction with the accompanying drawings forming part of this specification, wherein:

Fig. 1 is a diagrammatical illustration of a two- 45 Cowper's stove system according to the invention, and Figs. 2-4 are graphs illustrating the fluctuations of the temperature of various Cowper's stove systems.

Referring now to Fig. 1, 1 generally indicates a first 50 Cowper's stove or regenerating air heater or regenerating gas heater, and 2 generally indicates a second Cowper's stove or regenerating air heater or regenerating gas heater.

The heating gases introduced into the system through a line 3 enter the Cowper's stove 1 through the conduit 55 18 of a control valve 4 and the line 20, when the control valve 4 is in the position shown in full lines. The heating gases are burned and leave the Cowper's stove 1 as flue gases passing through the line 22 and the conduit 24 of another control valve 5 when the latter is in the position 60 shown in full lines. After passing the control valve 5, the flue gases reach the line 6, which conducts same through a heat accumulator 7 to the place or chamber 8 of action of a reactor, such as a blast furnace for example.

The blow air or blow gases introduced into the system 65 during the same time (first period) through a line 9 enter the other Cowper's stove 2 through the conduit 26 of the control valve 5 and the line 28, when said control valve 5 is in the position shown in the full lines. Said blow air or blow gases being discharged from the Cowper's stove 2 through the line 30 reaches a line 10

through the conduit 32 of the control valve 4, when the latter is in the position shown in full lines. The line 10 leads the blow air or blow gases through another heat accumulator 11 to the place or chamber 12 of action of a reactor, such as a blast furnace for example. The blow air or the blow gas passes through the heat accumulator 11 and the flue gas passes through the heat accumulator 7 at all times in the same direction.

Upon moving the control valves 4 and 5 into the position shown in dash lines for the performance of the second period, the heating gases or flue gases respectively pass through the Cowper's stove 2 and line 6 to the place 8 of action, while the blow air or blow gas passes through the Cowper's stove 1 and the line 10 to the place 12 of action.

Each heat accumulator 7 and 11 contains the usual means for collecting, storing, and transferring heat of the gases passing therethrough, as for example heat refractory stones or other material. As the blow air or gases leave the respective Cowper's stoves 1 and 2 during the blowing period thereof, they pass through the heat accumulator 11. During the beginning of the blowing period, the refractory material within the Cowper's stove has just been heated by the burning gas and is relatively hot. The blow gases passing therethrough are heated to a relatively high temperature, but lose some of their heat in heating the refractory material of the heat accumulator 11. As the blowing period progresses, the refractory material in the Cowper's stove loses some of its heat and the blow air or gases becomes relatively cooler, upon leaving the Cowper's stove. This loss of heat is however compensated by heat obtained when the gases pass through the heated refractory material of the accumulator 11. Thus, the gases arriving at the place of action 12 of the reactor are maintained at a substantially constant temperature over the entire blowing period. Similarly the burned flue gases entering the place of action 8 of a reactor are maintained at a substantially constant temperature by the accumulator 7.

In Figs. 2-4 the ordinate represents the temperature in degrees centigrade whereas the abscissa represents the time in hours. The curve 13 of Fig. 2 illustrates the periodic fluctuations of the temperature of a hitherto customary two-Cowper's stove system and the curve 14 of Fig. 3 illustrates the reduced fluctuations of the temperature of a hitherto customary three-Cowper's stove system. Curve 15 of Fig. 4, however, clearly indicates the largely reduced fluctuations of the temperature of a two-Cowper's stove system according to the invention.

As may be readily gathered from the graphs of Fig. 2-4, the two-Cowper's stove system according to the invention (see Fig. 4), including the arrangement of the heat accumulators 7 and 11, is much superior to the hitherto customary two-Cowper's stove system (see Fig. 2) and to the much more complicated three-Cowper's stove system in so far as the fluctuations of temperature are concerned.

When the multi-Cowper's stove system according to the invention is used for the operation of a blast furnace, the arrangement of the interposed heat accumulators renders possible the maintenance of a substantially uniform temperature of the blow air or blow gas prior to its entrance into the blast furnace, without necessitating a cooling off of the hot blow air or blow gas discharged from the Cowper's stove by subjecting the same to cold air by means of an automatically controlled valve. Owing to the arrangement of the heat accumulators according to the invention a mean temperature may be obtained which is between the two temperatures prevailing at the outlet of the Cowper's stove at the beginning and at the end of the period of blowing. If, however, a Cowper's stove system of hitherto customary arrangement is operated with a control of the temperature by a cold air valve, only the lower temperature prevailing during the end of the period at the outlet of the Cowper's

stove may be adjusted. Thus, the arrangement of a heat accumulator according to the invention renders possible to obtain a considerably higher temperature of the blow air or blow gas in existing blast furnaces and to build new installation in a less complicated and more economical manner, if only the hitherto customary temperature of the hot blow air or blow gas shall be obtained.

In a plant for production of city gas from low temperature carbonization gas, in which the plant operated in two periods of one-half hour each, utilization of the invention herein permitted temperature variations of 415° to 819° C. in the flue gas to be adjusted to a medium temperature of 617° C. The low-carbonization gas temperature was adjusted from a temperature variance between 589° and 861° C. to a mean temperature of 725° C. This was accomplished by using two heat accumulators.

The arrangement of heat accumulators according to the invention is also of great importance for the operation of low shaft blast furnaces, as the volume of action 20 of such a low shaft blast furnace is considerably smaller and, therefore, higher temperatures of the hot blow air or blow gas are more favorable.

We have described a preferred embodiment of our invention, but it is understood that this disclosure is for the 25 purpose of illustration, and that various omissions and changes in shape, proportion and arrangement of parts, as well as the substitution of equivalent elements for the arrangements shown and described may be made without departing from the spirit and scope of the invention as set forth in the appended claims.

For example the arrangement of heat accumulators according to the invention may also be made in multi-Cowper's stove systems having more than two Cowper's stoves.

What we claim is:

1. In a regenerating air heater system, the combination including a first and second reactor, a first and second Cowper stove for alternately feeding heated gases and burned flue gases respectively to said first and 40 second reactors respectively, means for feeding heating gases to each of said Cowpers for burning therein during a heating period, means for blowing gaseous medium through the heated Cowpers during a blowing period, whereby the gaseous medium is heated as it passes through the Cowpers' interior, conduit means connecting said first Cowper to said first reactor for transporting the gaseous medium to the latter, second conduit means connected to said second Cowper and said second reactor for transporting the burned flue gases to the latter, a heat accumulator in each of first and second conduit means 50 between the associated Cowper and reactor, said heat accumulator being adapted to collect heat from the gaseous medium and flue gases at the beginning of the blowing period and to transfer the collected heat to the gaseous medium and flue gases at the end of the blowing period, whereby the gaseous medium and burned flue gases entering the reactor are maintained at a substantially constant temperature over the entire blowing and heating cycle.

2. A regenerating air heater system according to claim 1, in which the heating gas feeding means and the gaseous medium blowing means includes valve means for the alternate feeding of heating gas and gaseous medium to be heated to each of said Cowpers, whereby one Cowper alternates respectively between a heating period and a blowing period, while the other Cowper simultaneously alternates respectively between a blowing period and a heating period.

3. In a regenerating air-heating system, the combination of a first and second Cowper stove, conduit means for connecting heating gases to one end of said first and second Cowper stoves, second conduit means for connecting burned flue gas to the opposite end of said first and second Cowper stoves, first and second reactors, first and second heat accumulators, means for

connecting said first reactor and said first accumulator in series to one end of said first and second Cowper stoves, means for connecting said second reactor and said second heat accumulator to the opposite end of said first and second Cowper stoves, first valve means 5 at one end of Cowper stoves for alternately directing heating gases to said first Cowper while said second Cowper is connected to said first accumulator and said first reactor and for thereafter connecting said second Cowper to said heating gas conduit and said first Cowper 10 to said first reactor and said accumulator, and second valve control means at the opposite end of said Cowpers for alternately connecting said first Cowper to said burned flue gas conduits and said second Cowper to

said second reactor and said second accumulator and thereafter for connecting said second Cowper to said burned flue gas conduit and said first Cowper to said second reactor and said second heat accumulator.
